United States Patent Office.

ADOLPH DELKESCAMP, OF BROOKLYN, NEW YORK, ASSIGNOR TO
THEODORE D. DAY, OF NEW YORK CITY.

Letters Patent No. 63,867, dated April 16, 1867.

IMPROVEMENT IN CLASPS FOR HOOP-SKIRTS.

The Schedule referred to in these Letters Patent and making part of the same.

TO ALL WHOM IT MAY CONCERN:

Be it known that I, ADOLPH DELKESCAMP, of Brooklyn, in the county of Kings, and State of New York, have invented, made, and applied to use a certain new and useful Improvement in Buttons or Clasps for Skeleton Skirts: and I do hereby declare the following to be a full, clear, and exact description of the said invention, reference being had to the annexed drawing, making part of this specification, wherein—

Figure 1 is a view of the piece of sheet metal as cut out to form the button or clasp.

Figure 2 is an elevation of the same as applied to a portion of a skirt; and

Figure 3 is a section of said button and the skirt facing.

These figures are in larger size than the actual articles usually are, in order to show the button or clasp more clearly, and similar marks of reference denote the same parts.

In the manufacture of skeleton skirts there is a space at the upper portion, where the hoops do not extend all the way around, and the ends of the bustle-hoops are united to each other by a facing, usually of kid, and button clasps are employed to hold the facing to the ends of said bustle-hoops. These button clasps have heretofore been made with hemispherical heads, from which teeth project that penetrate and clasp the facing to the hoops. The edges of the sheet metal, forming the hemispherical head, very often cut through and injure the kid facing.

The nature of my said invention consists in a button or clasp for skeleton skirts formed with an ornamental flange around the hemispherical or raised head, and with teeth to penetrate the facing or tape and clasp the hoop. This flange around the raised head prevents the kid or other material being cut through or injured by the clasp-button, and gives an ornamental finish to the said button.

In the drawing, *a* represents a portion of the facing of the skirt over the ends of the bustle-hoops *b*. *c* is my improved button or clasp with the hemispherical or raised head, 1, with the surrounding ornamental flange 2, and penetrating teeth 3, the same being cut out by dies and struck up to shape, and applied to hold the facing to the hoops as aforesaid. This button, with the raised head, may be made single, as shown, or with two united together. My button or clasp is a better article than those heretofore made, rendering the skirt more durable, and hence is a new and useful article of manufacture. The flange 2, surrounding the raised head, may be of any desired shape or width, and in fig. 4 I have shown the same with broader flanges than in the other figures. This button or clasp may be used on any part of the skirt to hold the hoops and tapes together.

What I claim, and desire to secure by Letters Patent, is—

The button or clasp for skeleton skirts, formed with the flange 2, the raised head 1, and the teeth 3, as and for the purposes specified.

In witness whereof I have hereunto set my signature this eighth day of June, A. D. 1866.

A. DELKESCAMP.
